Primary Examiner — Jennifer L Rempfer*Assistant Examiner* — Adrienne Corra(74) *Attorney, Agent, or Firm* — Myers Wolin, LLC(57) **CLAIM**

The ornamental design for a shoe as shown and described.

DESCRIPTION

FIG. 1 is a bottom perspective view of a shoe showing my new design, wherein the figure shows a right shoe and a left shoe is symmetric thereto;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top view thereof; and,

FIG. 7 is a bottom view thereof.

The broken lines shown illustrate portions of the shoe that form no part of the claimed design.

1 Claim, 6 Drawing Sheets(56)
